METHOD OF AND MACHINE FOR OPERATING UPON SHOE PARTS

Thomas C. Rowen, Swampscott, Mass., assignor to United Shoe Machinery Corporation, Paterson, N. J., a corporation of New Jersey

Application May 9, 1935, Serial No. 20,615

34 Claims. (Cl. 12—51)

This invention relates to improvements in methods of and machines for operating upon shoe parts and is herein exemplified with reference to the shaping of shoe parts, the pressing of seams in seamed shoe parts, and the application of a tape to a shoe part.

The area of a shoe upper part which may include a seam known as the "back seam," which joins the parts of a quarter or lining made of two sections, is a source of several difficulties in shoemaking which arise especially in connection with the operation of lasting the heel end of the quarter smoothly about the last, notwithstanding the variation in its width between the top or cone portion and the bottom. During the performance of this operation the quarter is subjected to considerable stress incident to making it conform to the shape of the last. If the quarter has a back seam the lasting operation is facilitated by finishing the seam as by rubbing or pressing it and by reinforcing it with a tape. However, if either of these operations is improperly carried out, as for example by straining the quarter excessively in lasting it or by rubbing or pressing the seam too vigorously, it is likely that the stress which necessarily accompanies the lasting operation will cause the stitches to show excessively, or to tear the stitching perforations, or in some instances even to break. Moreover, if the seam ridge is unevenly pressed toward one side or the other, a tape when applied to the upper over the ridge tends to hold the ridge in this distorted condition and hence is a detriment rather than an aid to shaping the back seam area of the upper into its desired condition.

It has been found that the above-mentioned difficulties in connection with operating upon a shoe quarter having a back seam are best minimized or avoided by operating upon it while it is in normally curved shape; and that uniformity in the pressed condition of the back seam at different points along its length is furthered not only by applying pressure simultaneously to all parts of the seam but also by limiting the lateral displacement of the seam ridge which is caused by this application of pressure. A method of this type and a machine operating in accordance with such a method are disclosed in Letters Patent of the United States No. 2,021,966, granted November 26, 1935, upon an application filed in the name of E. F. Schmidt.

With the foregoing in view, it is a general object of this invention to provide improved methods of and a machine for forming and pressing the back seam area of a shoe part or upper and applying

a tape thereto having the above-mentioned advantages and by the use of which is minimized even to a greater extent than heretofore the danger of broken stitches and the difficulty of shaping the upper in the vicinity of the back seam. 5

The invention in one aspect contemplates the method of shaping a shoe upper part which consists in urging spaced portions thereof away from each other thereby to tension the portions extending between such spaced portions and then applying pressure directly against the shoe part progressively from each of said spaced portions toward the other. As herein disclosed the operations referred to are preferably carried out while the shoe upper is supported by a form shaped in accordance with the shape which it is desired to impart to the upper. Accordingly, the back seam area of the shoe upper which is operated upon is first shaped into conformity to the form first by being tensioned over it so as to distribute the 20 shaping action over a substantial area of the upper and then by being pressed directly against the form.

When a seamed shoe part, such, for example, as a quarter having a back seam is operated upon in accordance with a method of this type the quarter is tensioned laterally of the seam thereby to reduce the depth of the seam crease as a result of portions at opposite sides of the seam being urged away from each other. However, to 30 insure against excessive straining of the seam widthwise thereof the invention also provides for limiting displacement of the portions of the shoe part contiguous to but exclusive of the seam laterally thereof, and then applying pressure to 35 the seam, thereby to reduce the height of the ridge and to flatten the seam crease. The displacement of the portions of the shoe part contiguous to the seam ridge at each side thereof is limited laterally of the seam, in the practice of 40 the above stated method, by gripping them while in their normally curved form and, accordingly, the tendency of the seam crease to be spread excessively as a result of the pressing of the ridge and hence to allow the stitches to become unduly 45 prominent is overcome. For similar reasons it is apparent that there is little or no increase in the tension of the stitches as a result of the pressing of the seam ridge, and for this reason also the likelihood of the seam's being impaired 50 either by the pressing of the ridge or in the lasting operation is reduced to the utmost.

While the procedures stated above may be carried out for the purpose of shaping a shoe part and finishing the back seam, if, in fact, the shoe 55

part has one, they may also be of great value as operations preparatory to the application of a piece of tape over the seam for the purpose of reinforcing it. Accordingly, the invention in 5 another aspect provides a method of taping a seam which includes the step of applying a piece of tape over the ridge of a seam of a work piece which has been operated on in accordance with any of the procedures referred to above.

10 One illustrative machine arranged and adapted to operate in accordance with the methods stated above and embodying important features of the invention to be more specifically described hereinafter, includes a form shaped and arranged to 15 support and shape the concave surface of a shoe part adjacent to the seam in its normally curved form, the work engaging surface of the form being interrupted to receive the seam ridge, means cooperating with the form to press portions of 20 the shoe part contiguous to but exclusive of the seam into conformity to the shape of the form, and means mounted for movement within the interruption in the form to press the entire length of the seam ridge simultaneously, thereby to reduce its height and to flatten the seam crease. As 25 mentioned above in connection with the method aspect of the invention, the gripping of portions of the shoe part contiguous to the seam, which results from their being pressed, prevents excessive spreading of the parts of the shoe upper contiguous to the seam crease which otherwise might 30 result from the pressing of the seam ridge. Furthermore, the seam ridge is not only reduced along its entire length simultaneously but is also 35 prevented from being displaced either to one side or to the other, being under control of the interrupted surfaces of the form between which the ridge extends.

The machine in which the invention is illustrated as embodied also comprises means for 40 tensioning the shoe part laterally of the seam to make the shoe part conform to the shape of the form. Preferably this means is arranged to urge portions of the shoe part at opposite sides of the 45 seam away from each other to accomplish this result; but the invention also contemplates the provision of other means arranged to impart a succession of wiping strokes as it is moved toward the form, and to this end is constituted by sets 50 of wipers carried by the above-mentioned pressing means, which wipers are mounted and arranged to be moved successively into engagement with the shoe part before the seam is pressed and subsequently to separate from each other and 55 thereby frictionally to tension the shoe part laterally of the seam as the pressing means is moved toward the form.

As herein illustrated and in accordance with another feature of the invention, the form which 60 shapes and supports the work piece comprises two sections which are spaced to receive the seam ridge therebetween, not only to provide the interruption in their work supporting surfaces referred to above by which lateral displacement of the seam ridge is prevented, but also to permit the 65 member for pressing the seam ridge to be moved into such a position that its work engaging surface becomes continuous with that of the forms in order to effect a complete pressing of the seam ridge and to afford a smooth supporting surface for a tape if the machine is to be used for tape applying.

With the latter purpose in view, the operating mechanism for the forms, shaping member and seam pressing member is so constructed, in ac-

cordance with another feature of the invention, that the shaping member can be moved away from the forms a limited amount, to facilitate the insertion of a piece of tape between the forms and the shoe part, without moving the seam 5 pressing member, whereby the continuity of the tape supporting surface is preserved.

These and other features of the invention will now be more particularly described by reference to the accompanying drawings and pointed out in the appended claims.

In the drawings,

Fig. 1 is a view in front elevation illustrating one embodiment of the invention;

Fig. 2 is a view in side elevation of the machine 15 illustrated in Fig. 1;

Fig. 3 is a sectional plan view of the machine, portions of the base of which have been broken away, the section being taken along the line III—III of Fig. 2;

Fig. 4 is a front elevation of portions of the operating instrumentalities, a portion of which, in section, illustrates their relation before the seam pressing member acts upon the seam ridge;

Fig. 5 is another sectional front elevational view of the mechanism illustrated in Fig. 4 but showing the pressing member as having operated upon the seam ridge;

Fig. 6 illustrates the application of a tape over the seam ridge, the operating instrumentalities 30 being shown in section;

Fig. 7 illustrates an undesirable condition of a pressed seam which is avoided by practicing the present invention;

Fig. 8 is a view in perspective of an alternative form of pressing and shaping member, parts of which are broken away, illustrating an intermediate stage of the pressing and shaping operation; and

Fig. 9 is an end elevation of a part of the structure illustrated in Fig. 8 but representing the proximal relation of the form pressing member and work piece.

A shoe quarter Q the back seam of which is to be pressed and have a tape applied thereto in 45 a machine of the type illustrated herein, as will be more fully described below, is first shaped both longitudinally and laterally of the seam ridge *r* over forms 10 and 12, the upper portions of which are convexly shaped and are complementary to the 50 desired shape of the concave side of the shoe part Q in the vicinity of the back seam. The shoe part Q is first made to conform to the shape of the forms 10 and 12 by being pressed downwardly thereabout by two sets of spring wipers 55 14 and 16, these wipers being carried by a shaping member 18 and being arranged and adapted successively to engage the shoe part Q and to 60 yield outwardly so as to allow continued downward movement of the shaping member 18 until the latter firmly presses the shoe part Q against the top portions of the forms 10 and 12. From the time when the wipers 14 and 16 engage 65 the shoe part Q until their downward movement is terminated they frictionally tend to move the shoe part Q downwardly into contact with the forms 10 and 12 and to tension it transversely of the seam ridge *r* so as to diminish, as much as possible, the depth of the crease of the back seam at its convex side. Simultaneously with the aforesaid tensioning of the shoe part Q, the forms 10 and 12 are swung toward each other 70 about a common axis 20 to confine the seam ridge against any lateral displacement between surfaces 22 and 24 on the forms 10 and 12, respec- 75

tively. After the sides of the seam ridge r have thus been gripped or confined against lateral displacement between the surfaces 22 and 24, as illustrated in Fig. 4, the seam ridge is reduced 5 heightwise by a seam pressing member 26 which is adapted to be operated between the surfaces 22 and 24 toward the form 18 so as to compress the seam ridge, and also further to improve the continuity of the convex surface of the shoe part 10 crosswise of the seam crease by flattening the latter against the shaping member 18.

The general operating characteristics of the illustrated machine having been described, the construction and arrangement of its various features will now be set forth in detail. The forms 10 and 12 as herein illustrated are shaped in accordance with the normal curvature of a shoe quarter at the vicinity of the back seam and are mounted to swing on trunnions 28, 30 the former 20 of which is fixed in the upper end of a standard 32 mounted on a base plate 34. Extending upwardly from one side of the base plate 34 is a column 36 having a transverse bore which receives the trunnion 30 in axial alinement with the 25 trunnion 28. Slideways 38 extending vertically in the column 36 are arranged to receive a slide 40 the upper end of which is curved toward the forms 10 and 12 and is bored to receive a pin 42 on which the shaping member 18 is mounted.

30 The slide 40 is moved upwardly and downwardly in the column 36 by a rod 44 which may be operated by any convenient means such as a treadle, for example. The rod 44 passes through a clearance hole in a lug 46 formed integral with the slide 40 and acts against the lug 46 to lower the shaping member through a spring 48 the upper end of which abuts against a collar 50 which can be adjustably clamped to the rod 44 in any desired position. Upon depressing the 40 rod 44, therefore, the shaping member 18 is yieldingly pressed against the shoe part Q but its retraction is effected positively owing to the provision of a collar 52 fixed to the rod 44 and adapted to engage the lower side of the lug 46.

45 The wipers 14 are each formed from spring sheet material which is slotted, as indicated in Fig. 2, to provide a plurality of fingers which can yield relatively to each other so as to accommodate the different curvatures of different parts 50 of the forms 10 and 12. The wipers 16 are formed in the same way as the wipers 14 both of which sets of wipers are fastened to the shaping member 18 by screws 54. It will be understood with reference to Fig. 1, that when the 55 shaping member 18 is lowered the wipers 14 act upon the shoe part Q first and impart an initial tension thereto transverse to the seam ridge and cause the portion of the quarter Q extending between the wipers over the upper part of the forms 10 and 12 to be held thereagainst. Just prior to the time when the shaping member 18 is brought into engagement with the quarter Q the wipers 16 engage the latter and in being forcibly moved along the sloping sides of the 60 forms 10 and 12 separate and impart an increased tension to the shoe part, already tensioned by the wipers 14, crosswise of the seam ridge r thereby to insure that the portions of the quarter adjacent to the seam will be abruptly 65 curved away from each other at the crease and hence result in a substantially continuous surface on the convex side of the shoe part considered transversely of the seam.

70 As stated above, while the above described action of the wipers 14 and 16 is occurring the

forms 10 and 12 are moved toward each other, to cause the surfaces 22 and 24 to confine the sides of the seam ridge r , by mechanism which will now be described. The end surface 56 of the slide 40 is arranged, when the slide is lowered, to engage a spring 58 seated within a recess in a rack 60 slidably mounted in the slideways 38. A segmental gear 62 meshing with the rack 60 is pinned to one end of a shaft 64 to the opposite end of which is also pinned another segmental gear 66, the latter being arranged to mesh with a sliding rack bar 68 mounted for vertical movement in slideways 70 formed in the column 36. By means of the connections described above, lowering of the shaping member 18 also causes the bar 68 to be moved downwardly which movement causes the forms 10 and 12 to be swung toward each other through connections comprising toggle links 72, 74 which are pivotally connected to the bar 68 by a pin 76, and by other pins 77 20 to the lower ends of arms 78 and 80 which extend downwardly from the forms 10 and 12, respectively.

The effect of operating the rod 44 downwardly on the mechanism thus far described is first, 25 through the spring 48, yieldingly to bring the shaping member 18 into contact with the shoe part Q. Thus, when the reference line x at the work engaging surface at the shaping member in Fig. 1 reaches the position indicated at a , the 30 wipers 14 begin to act upon the shoe part so as to tension it crosswise of the seam and to make it conform to the surfaces of the forms 10 and 12. This action occurs alone until the shaping member is lowered to the position of the reference 35 line b , at which point the end surface 56 of the slide 40 engages the spring 58 and initiates the swinging movement of the forms 10 and 12 toward each other to confine the seam ridge r against lateral displacement. The above 40 described action of the wipers 14 and 16 and this last-mentioned swinging movement of the forms 10 and 12 occur simultaneously throughout the downward movement of the shaping member 18 until it reaches the position indicated by the 45 reference line c , at which point its downward movement is arrested by contact with the quarter 50 Q which now is pressed against the forms 10 and 12. However, further downward movement of the rod 44 is permitted by the yielding connection 55 between it and the slide 40 and also the yielding connection between the slide 40 and the rack bar 60. Downward movement of the rod 44 in excess of that required to bring the shaping member 18 into contact with the quarter Q causes the seam 60 pressing member 26 to be positively elevated into engagement with the seam ridge thereby to reduce its height and to press the seam, as indicated at Fig. 5, as will now be described. The pressing member 26 is mounted to slide vertically 65 in slideways 82 formed integrally with and extending upwardly from the base plate 34. The pressing member 26 is raised and lowered by toggle connections including a link 84 which is pivoted at its upper end at 86 to the pressing 70 member 26, and at its lower end to the upper end of a link 88 the lower end of which is pinned to a shaft 90 rotatably mounted in the slideways 82. The shaft 90 is operated by a lever 92 fixed thereto and having a bifurcated end adapted to receive 75 the rod 44, a certain part of the downward movement of which is transmitted to the lever 92 by a collar 94 which may be adjustably clamped on the rod 44 in any desired position and which bears against the bifurcated end of the lever 92 when 75

the rod 44 is lowered beyond that position required to carry the shaping member 18 to the position indicated by the reference line c. It will be apparent that such movement of the rod 44 causes the lever 92 to be swung in a counterclockwise direction (Fig. 2) so as to straighten the toggle comprising the links 84, 88 and hence to elevate the seam pressing member 26 until its pressing surface is substantially continuous with the upper surfaces of the forms 10 and 12, as illustrated in Fig. 5. A collar 96 fixed to the shaft 44 below the lever 92 acts, when the rod 44 is raised a substantial distance, to break the toggle 84, 88 and hence to lower the seam pressing member 26. Similarly to insure that the toggle comprising the links 72, 74 shall be broken to effect the separation of the forms 10 and 12 a rod 98 threaded into the rack bar 60, and telescoping within a bore 100 in the slide 40, has formed near its upper end a shoulder 102 which is adapted to be engaged by the inner end of a screw 104 carried by the slide 40. Thus, as the slide 40 is raised well above the forms 10 and 12 after the completion of a seam pressing operation the screw 104 is raised into engagement with the shoulder 102 and subsequent upward movement of the slide thus causes the rod 98 to be raised and hence the toggle 72, 74 to be broken.

The seam pressing member 26, as embodied in the illustrated machine, is provided with an electric resistance heating unit 106 which heats not only the pressing member 26 but also the forms 10 and 12 between which and the pressing member, as illustrated in Figs. 4 and 5, there is a substantial area of heat transferring surfaces.

The operating mechanism of the illustrated machine is so arranged as to adapt it for applying a piece of tape over the ridge of a seam after it has been pressed in the manner referred to above. With this object in view, the shaping member 18 can be raised sufficiently from the quarter, after its seam ridge has been pressed, to allow the introduction of a tape between the forms 10 and 12 and the quarter without either separating the forms 10 and 12 or lowering the presser member 26. Thus, the supporting surface for the tape remains continuous and undisturbed as tape applying pressure is brought to bear upon the quarter by the shaping member 18. The adhesion of the tape to the quarter is further facilitated by the heat of the forms 10 and 12 and pressing member 26 provided by the heating member 106. The height to which the shaping member 18 can be raised without separating the forms 10 and 12 or lowering the pressing member 26 can be readily controlled by adjusting the collar 96 on the rod 44 which breaks the toggle for operating the pressing member 26, and by locating the screw 104 as desired with respect to the shoulder 102.

As illustrated in the embodiment of the invention represented in Figs. 8 and 9, a shaping member 108, adapted to be mounted on the slide 40 in the same way that the shaping member 18 is mounted thereon, is constructed and arranged, as will be more fully described hereafter, first to tension a shoe part on the forms 10 and 12 transversely of its seam ridge, if in fact the shoe part has a seam ridge, and then to apply shaping pressure over the entire tensioned area of the shoe part, such shaping pressure being applied progressively from each tensioned area toward the other.

The shaping member 108 is pivotally mounted on the slide 40 on the pin 42 so as to be capable

of self adjustment longitudinally of the forms 10 and 12. The work-engaging surface of the shaping member 108 is curved in conformity to the shape of the forms 10 and 12 both laterally and longitudinally thereof. Arms 110, 112 are fixed to the end of the shaping member 108 and carry at their ends studs 114, 116 on which are rotatably mounted other shaping members 118 and 120, respectively. The inner sides of the shaping members 118 and 120 are recessed to receive inserts 122, 124, respectively, of yieldable material such as rubber for example, and which are adapted to yield into intimate contact with the work-piece throughout its area which they cover when held thereagainst. The work-engaging surfaces of the inserts 122 and 124 are also shaped both laterally and longitudinally in conformity to the contour of the forms 12 and 10, respectively, but normally, when disposed well above the forms, are swung on the studs 114, 116 by means of a spring 126 abutting lugs 128, 130 extending upwardly from the shaping members 118 and 120, respectively, so that the distance between their lower edges is less than the distance between the sides of the forms 10 and 12. The extent to which the lower parts of the shaping members 118 and 120 can thus be swung toward each other may be adjustably limited by a bolt 132 which extends through the upper ends of the lugs 128 and 130.

It will now be apparent that as the slide 40 carrying the shaping member 108 is lowered, the lower edges of the inserts 122 and 124 will first engage spaced portions of a work-piece on the forms 10 and 12 and then as a result of being moved downwardly exert oppositely directed frictional forces tending to tension the area of the work piece extending between the portions first engaged by the inserts 122, 124. Thus, if the work-piece has a seam, as in the case of the work-piece illustrated in Figs. 8 and 9, it is tensioned laterally of the seam whereby the continuity of the surface of the work-piece is improved by diminishing the depth of the seam crease. Still further downward movement of the shaping member 108 causes the shaping members 118 and 120 gradually to swing so that more and more of the upper portions of the work-engaging surfaces of the inserts 122 and 124 are brought into contact with the work-piece. Thus, shaping pressure is applied to the work-piece progressively from the sides of the work-piece upwardly and over the rear portion thereof which includes the back seam of shoe parts having such seams. It will be noted from Fig. 9 that the yielding inserts 122 and 124, in response to shaping pressure, are expanded widthwise of the forms 10 and 12 into contact with or contiguous relation to the shaping member 108 as a result of being compressed to a slight extent. Accordingly, at the final stage of the pressing operation the work-piece is pressed against the forms 10 and 12 continuously over its entire area covered by the shaping members 108, 118 and 120.

While the operation of the machine will be understood from the foregoing description of both embodiments of the invention, it will now be briefly summarized with reference to the use of a shaping member of the type illustrated in Fig. 1, the operation of the other type of shaping member as illustrated in Fig. 8 already having been outlined above. The proper adjustments of the machine having been made as described above with reference to the character of the quarter Q to be operated upon, the operator lowers the rod 44 as by a treadle or other equivalent mechanism,

at the same time positioning the quarter over the forms 10 and 12 so that the seam ridge extends downwardly between the surfaces 22, 24. As the shaping member 18 is moved downwardly the 5 wipers 14 and 16 are brought into action successively to make the portions of the quarter contiguous to the seam at each side thereof conform to the shape of the forms 10 and 12 and also to tension the quarter transversely of the seam to 10 reduce the depth of the seam crease as much as practicable in this manner. During the latter part of the downward movement of the shaping member 18 the forms 10 and 12 are swung toward each other as described above to grip or confine 15 the sides of the seam ridge against lateral displacement when the ridge is acted upon by the seam pressing member 26. After the shaping member 18 has been moved firmly into engagement with the portions of the quarter Q contiguous to the seam, the seam pressing member 26 is operated positively upwardly into engagement with the entire length of the seam ridge simultaneously and compresses the latter so as to reduce the height of the ridge and also still further to flatten the seam crease on the convex side of the quarter. It will be apparent from the foregoing that the confinement of the seam ridge between the surfaces 22 and 24 as it is pressed insures against the ridge being displaced either 20 to one side or the other at any point along its length. Consequently, the seam ridge, when completely pressed, is straight and uniformly reduced in height from one end to the other, a condition which is much to be desired, especially if this operation is to be followed by the application of the tape over the seam ridge. Moreover, on account of the portions of the quarter Q contiguous to the seam being held against displacement laterally of the seam the seam pressing member 26 causes 25 the individual parts of the quarter to be relatively abruptly curved at their junction without gaping at the seam crease and hence minimizes the tendency of the stitches to "grin" as in the case of the work piece illustrated in Fig. 7, or to 30 enlarge the stitch perforations as is caused by some seam pressing operations in which the ridge is not controlled against lateral displacement or may receive pressure concentrated in a small locality. 35

50 The ridge of the seam now having been reduced until it is substantially continuous with the concave side of the work piece, if the machine is used only for seam pressing the shaping member 18 may be allowed to rise to its uppermost position, as illustrated in Fig. 1. However, if a tape is to be applied over the pressed seam, the shaping member 18 is raised only far enough to allow the insertion of a tape between the quarter Q (the quarter also being raised owing to the gripping 40 action of the wipers 14) and the portions of the forms 10 and 12 and the pressing member 26 beneath the area of the quarter to be covered by the tape. By thus raising the shaping member 18 to a limited extent, the forms 10 and 12 are 45 not separated and the pressing member 26 is not lowered to interrupt the continuity of their work engaging surfaces. The shaping member 18 is then again lowered to cause the tape to be pressed against the quarter, as illustrated in Fig. 6, with sufficient dwell to insure complete attachment of 50 the tape to the quarter. Later the shaping member 18 may again be retracted to the position it occupies in Fig. 1, to facilitate the placement of an untreated quarter over the forms, as described 55 above.

It is to be understood that the taping operation is carried out in the same way and by the same succession of movements by the operator in the use of pressing members of each type illustrated in Figs. 1 and 8.

Having thus described my invention, what I claim as new and desire to secure by Letters Patent of the United States is:

1. In a machine for operating upon a curved shoe part having a seam ridge extending from its 10 concave surface, a form shaped and arranged to support and shape the concave surface of the shoe part into its normally concave state, the work engaging surface of said form being interrupted to receive the seam ridge, means for pressing portions of the shoe part contiguous to but exclusive 15 of the seam ridge against said form, and a member shaped and mounted for movement within said interruption in said form to press the seam ridge. 20

2. In a machine for operating upon a curved shoe part having a seam ridge extending from its concave surface, means shaped and arranged to support and form the concave surface of the shoe part in its normally concave state comprising 25 forms spaced to receive the seam ridge therebetween, means cooperating with said forms to grip portions of the shoe part contiguous to but exclusive of the seam ridge, and a pressing member mounted for movement between said forms 30 into engagement with the seam ridge.

3. In a machine for operating upon a curved shoe part having a seam ridge extending from its concave surface, means shaped and arranged to support and form portions of the concave surface of the shoe part contiguous to but exclusive 35 of the seam ridge in their normally concave state, a shaping member mounted for movement into engagement with the said portions of the shoe part, means cooperating with said shaping member to press the seam ridge, said means being shaped and mounted for movement into engagement with the seam ridge, and operator-controlled means for moving said shaping member and said last-mentioned means successively into 40 45 engagement with the shoe part.

4. In a machine for operating upon a curved shoe part having a seam ridge extending from its concave surface, forms spaced to receive the seam ridge therebetween and movable toward each 50 other thereby to straighten the seam ridge, said forms being shaped and arranged to support the concave surface of a shoe part in its normally curved state, shaping means mounted for movement into engagement with portions of the shoe 55 part contiguous to but exclusive of the seam ridge, a presser member mounted for movement between said forms into such a position that its pressing surface is continuous with that of the forms, and operator-controlled means for causing 60 said shaping means and pressing member successively to engage the shoe part, said operator-controlled means being operable to retract the shaping means to a limited extent without moving said pressing member. 65

5. In a machine for operating upon a curved shoe part having a seam ridge extending from its concave surface, forms shaped and arranged to support and shape the concave surface of a shoe part adjacent to the seam in its normally 70 curved form, the forms being spaced to receive the seam ridge therebetween, a shaping member cooperating with said forms to press portions of the shoe part contiguous to the seam into conformity to the shape of the forms, and means 75

adapted to be operated as said member is moved toward the forms to impart to the shoe part laterally of the seam a succession of oppositely directed wiping strokes, and means mounted for movement between said forms and shaped to engage the entire length of the seam ridge simultaneously thereby to reduce its height and to flatten the seam crease.

6. In a machine for operating upon a curved shoe part having a seam ridge extending from its normally concave surface, forms shaped and arranged to support the concave surface of the shoe part adjacent to the seam in its normally curved state, said forms being spaced to receive the seam ridge therebetween, means for pressing portions of the shoe part contiguous to the seam against the forms, said pressing means carrying members adapted to be moved into engagement with the shoe part as the pressing means is moved toward it to tension the shoe part laterally of the seam, and means disposed between said forms shaped and mounted to press the entire length of the seam ridge simultaneously.

7. In a machine for operating upon a curved shoe part having a seam ridge extending from its normally concave surface, means constructed and arranged to support and shape the concave surface of the shoe part adjacent to the seam in its normally concave form, the work-engaging surface of said means being interrupted to receive the seam ridge, means shaped and mounted to press the entire length of the seam ridge simultaneously, a member for pressing the portions of the shoe part including and contiguous to the seam against both of said pressing means, and sets of yielding wipers carried by said member mounted and arranged to engage the shoe part before the seam is pressed and impart thereto successive applications of frictional force directed laterally of the seam.

8. In a machine for operating upon a curved shoe part having a seam ridge extending along its normally concave surface, a form shaped and arranged to support and shape the concave surface of the shoe part in its normally concave state, the work-engaging surface of said form being interrupted to receive the seam ridge, a member shaped and mounted for movement relatively to said form to press the seam ridge, means for pressing the shoe part against said form and pressing member, and means cooperating with said form adapted to be operated before the last-mentioned means engages the shoe part to impart wiping strokes to the shoe part directed oppositely to each other away from the seam.

9. In a machine for operating upon a curved shoe part having a seam ridge extending along its normally concave surface, a form shaped and arranged to support and shape the concave surface of the shoe part in its normally concave state, the work-engaging surface of said form being interrupted to receive the seam ridge, a member shaped and mounted for movement relatively to said form to press the seam ridge, means for pressing the shoe part against said form and pressing member, and wipers adapted to be moved into engagement with the shoe part before the seam is pressed, said wipers being mounted to separate from each other and frictionally to tension the shoe part laterally of the seam as the pressing member is moved toward the form.

10. In a machine for operating upon a curved shoe part having a seam ridge extending along its normally concave surface, a form shaped and arranged to support and shape the concave surface

of the shoe part in its normally concave state, the work-engaging surface of said form being interrupted to receive the seam ridge, a member shaped and mounted for movement relatively to said form to press the entire length of the seam ridge simultaneously, means for pressing the shoe part against said form and pressing member, and a plurality of wipers carried by said pressing member and arranged to engage the shoe part in succession whereby one set of wipers acts upon a portion of the shoe part previously tensioned by another set of wipers.

11. That improvement in methods of operating upon a shoe part having a normally curved surface from which a seam ridge extends which consists in forming the shoe part at the vicinity of the seam into its normally curved state, holding portions of the shoe part at each side but exclusive of the seam ridge against displacement laterally thereof, and then applying pressure to the seam ridge thereby to reduce the height of the ridge and to flatten the seam crease.

12. That improvement in methods of operating upon a shoe part having a normally concave surface from which a seam ridge extends which consists in forming the shoe part at the vicinity of the seam into its normally curved state, gripping while in their normally curved form portions of the shoe part contiguous to but exclusive of the seam ridge, and then applying pressure to the seam ridge throughout its entire length simultaneously thereby to reduce the height of the rib and to flatten the seam crease.

13. That improvement in methods of operating upon a seamed shoe part having a normally concave surface from which a seam ridge extends which consists in forming the shoe part at the vicinity of the seam into its normally curved state, holding against displacement laterally of the seam portions of the shoe part contiguous to but exclusive of the seam ridge, and then applying pressure to the seam ridge throughout its entire length simultaneously.

14. That improvement in methods of operating upon a shoe quarter having a seam ridge extending from its normally concave surface which consists in tensioning the shoe quarter laterally of the seam, the quarter at the vicinity of the seam being shaped in its normally curved state, gripping while in their normally curved form portions of the quarter contiguous to but exclusive of the seam, and then applying pressure to the seam and the seam ridge throughout its entire length simultaneously thereby to reduce the height of the ridge and to flatten the seam crease.

15. That improvement in methods of operating upon a shoe quarter having a seam ridge extending from its normally concave surface which consists in tensioning the quarter laterally of the seam over a form shaped and arranged to support the quarter at the vicinity of the seam in its normally curved state, while the quarter is thus tensioned applying pressure to the portions of the quarter contiguous to the seam without applying to the seam or seam ridge any pressure directed heightwise of the ridge, and then applying pressure to the seam and the seam ridge throughout its entire length simultaneously thereby to reduce the height of the ridge and to flatten the seam crease.

16. That improvement in methods of operating upon a curved shoe part having a seam ridge extending from its normally concave surface which consists in tensioning the shoe part trans-

versely of the seam while holding the shoe part at the vicinity of the same in its normally curved state, confining the sides of the seam ridge against lateral displacement, and then applying pressure 5 successively to portions of the shoe part contiguous to the seam and to the seam ridge throughout its entire length simultaneously thereby to reduce the height of the ridge and to flatten the seam crease.

10 17. That improvement in methods of operating upon a curved shoe part having a seam ridge extending from its concave surface which consists in imparting to the shoe part laterally of the seam a succession of oppositely directed wiping strokes, confining the sides of the seam ridge against lateral displacement, gripping while in their normally curved form portions of the shoe part contiguous to the seam, and then applying pressure to the top of the seam ridge throughout 15 its length simultaneously thereby to reduce its height and to flatten the seam crease.

18. That improvement in methods of operating upon a shoe quarter having a seam ridge extending from its normally concave surface which consists in tensioning the quarter laterally of the seam over a form shaped substantially complementary to the normally curved form of the quarter at the vicinity of the seam, pressing the upstanding portions of the seam ridge against 25 each other, gripping while in their normally curved form portions of the quarter contiguous to the seam, and then applying pressure heightwise of the seam ridge throughout its entire length simultaneously thereby to reduce the 30 height of the seam ridge and to flatten the seam crease.

19. That improvement in methods of operating upon a shoe part having a normally concave surface from which a seam ridge extends which 40 consists in forming the shoe part at the vicinity of the seam in its normally curved state, limiting displacement of the portions of the shoe part at each side of the seam ridge laterally thereof, applying pressure to the seam throughout its 45 entire length simultaneously thereby to reduce the height of the ridge and to flatten the seam crease, and then applying an adhesive tape to the concave side of the shoe part over the seam ridge.

50 20. That improvement in methods of operating upon a shoe part having a normally concave surface from which a seam ridge extends which consists in forming the shoe part at the vicinity of the seam in its normally curved state, limiting 55 displacement of both the seam ridge and portions of the shoe part at each side of the seam ridge laterally thereof, applying pressure to the seam throughout its entire length simultaneously thereby to reduce the height of the ridge and 60 to flatten the seam crease, and then affixing an adhesive tape to the concave side of the shoe part over the seam ridge by pressing the tape against the shoe part simultaneously at all points thereof covered by the tape.

65 21. That improvement in methods of operating upon a shoe part having a normally concave surface from which a seam ridge extends which consists in forming the shoe part at the vicinity of the seam into its normally curved state, holding 70 against displacement laterally of the seam portions of the shoe part contiguous to but exclusive of the seam ridge, applying pressure to the seam ridge throughout its entire length simultaneously, and then affixing an adhesive tape to the 75 concave side of the shoe part by the application

of heat and pressure simultaneously throughout the area of the shoe part covered by the tape.

22. That improvement in methods of operating upon a curved shoe part having a seam ridge extending from its normally concave surface 5 which consists in tensioning the shoe part transversely of the seam while holding the shoe part at the vicinity of the seam in its normally curved state, confining the sides of the seam ridge against lateral displacement, applying pressure 10 successively to portions of the shoe part contiguous to the seam and to the seam ridge throughout its entire length simultaneously thereby to reduce the height of the ridge and to flatten the seam crease, and then applying an adhesive 15 tape to the concave side of the shoe part over the seam ridge.

23. That improvement in methods of shaping a shoe upper part over a form which consists in successively urging spaced portions at the edges 20 of the area which is operated upon away from each other thereby to tension over the form the portions of the shoe part intermediate between said spaced portions and then applying pressure directly against the tensioned portions of the 25 shoe part progressively from the edges of the area to be operated upon toward the central portion thereof.

24. That improvement in methods of shaping a shoe upper part which consists in urging spaced 30 portions of the shoe part away from each other thereby to tension the portions of the shoe part extending between such spaced portions and then applying pressure directly against the shoe part progressively from each of said spaced portions 35 toward the other.

25. That improvement in methods of operating upon a seamed shoe part, which consists in urging portions of the shoe part at opposite sides of the seam away from each other thereby to 40 tension the shoe part transversely of the seam, applying pressure to the shoe part progressively from the said spaced portions toward the seam thereby to hold against displacement portions of the shoe part contiguous to but exclusive of the 45 seam and then applying pressure to the seam.

26. That improvement in methods of operating upon a seamed shoe part which consists in urging spaced portions of the shoe part at opposite sides of the seam away from each other thereby to 50 tension the shoe part transversely of the seam, applying pressure to portions of the shoe part contiguous to but exclusive of the seam thereby to hold them against displacement, and then applying pressure to the seam.

27. In a machine for operating upon a curved shoe part having a seam ridge extending from its normally concave surface, a heated form shaped and arranged to support and shape the concave surface of the shoe part into its normally concave state, pressing means mounted for movement toward and away from the form, said means being constructed and arranged progressively to operate on the shoe part toward the seam ridge from points at each side thereof.

28. In a machine for operating upon a curved shoe part, a heated form shaped and arranged to support and shape a shoe part pressed thereagainst, and means cooperating with said form to tension the shoe part over the form and progressively to apply shaping pressure directly against the shoe part from the edge of the area of the shoe part engaged by said means toward the center thereof.

29. In a machine for operating upon a shoe 75

upper part having a normally concave surface, a convexly shaped form arranged to engage and shape the concave surface of the shoe part into its normally concave state, means for pressing the shoe part into engagement with the form arranged yieldingly to urge opposite spaced portions of the shoe part away from each other thereby to tension portions of the shoe part between said opposite points over the form and progressively to apply pressure directly against the shoe part from the edges of the area engaged by said pressing means toward the center thereof.

30. In a machine for operating upon a seamed shoe part, a form, means for pressing the shoe part into engagement with the form constructed and arranged successively to urge spaced portions of the shoe part at opposite sides of the seam away from each other thereby to tension the shoe part transversely of the seam and then to hold the portions of the shoe part contiguous to but exclusive of the seam against the form, and means cooperating with said pressing means for applying pressure to the seam.

31. In a machine for operating upon a shoe upper part having a normally concave surface, a convexly shaped heated form arranged to support and shape the concave surface of the shoe part into its normally concave state, and a pressing member movable into engagement with the shoe part on the form, the pressing surface of said pressing member normally having a greater curvature than that of the supporting surface of the form and being adapted to be shaped into conformity to the shape of the form by yielding and exerting shaping pressure directly against the shoe part progressively from the edges of the area to be operated upon by the pressing member toward the center thereof.

32. In a machine for operating upon a shoe upper part, a heated form, and a pressing member for pressing the shoe part into engagement with

the form, the pressing surface of said member being adapted to yield into conformity to the shape of the form in response to pressure therebetween, said pressing surface being shaped progressively to engage and apply pressure to the shoe part from the marginal portion of the area of the shoe part to be operated upon toward the center thereof.

33. In a machine for operating upon a seamed shoe part, a form shaped and arranged to support a substantial area of the shoe part at each side of the seam, pressing means mounted for movement toward the form yieldingly to urge spaced portions of the shoe part on opposite sides of the seam away from each other, thereby to tension the shoe part transversely of the seam over the form, the pressing surface of said member also being adapted to yield and exert shaping pressure directly against the shoe part progressively from the edges of the area operated upon by the pressing member toward the seam.

34. In a machine for operating upon a curved shoe part having a seam ridge extending from its concave surface, forms spaced to receive the seam ridge therebetween thereby to limit its lateral displacement, said forms being shaped and arranged to support the concave surface of a shoe part in its normally curved state, shaping means mounted for movement into engagement with portions of the shoe part contiguous to but exclusive of the seam ridge, a presser member mounted for movement between said forms into such a position that its pressing surface is continuous with that of the forms, and operator-controlled means for causing said shaping means and pressing member successively to engage the shoe part, said operator-controlled means being operable to retract the shaping means to a limited extent without moving said pressing member.
